United States Patent Office.

ALFRED GERARD, OF SOMERSET COUNTY, NEW JERSEY.

Design No. 2,795, dated October 1, 1867.

DESIGN FOR A WATCH-PLATE.

The Schedule referred to in these Letters Patent and making part of the same.

TO ALL WHOM IT MAY CONCERN:

Be it known that I, ALFRED GERARD, of Somerset county, in the State of New Jersey, have invented or produced a new and original Design for Watch-Plates; and I do hereby declare the following to be a full, clear, and exact description of the same, reference being had to the annexed drawing, making part of this specification, wherein—

Figure 1 is a view of the said watch-plates on about twice the ordinary size, and

Figure 2 is a side view of the same.

a is the plate known as the three-quarter plate, carrying the arbor of the minute-hand, the spring-barrel arbor, and the click or pawl to the winding-wheel. This plate *a* is of the shape and configuration represented. *b* is the plate or bridge that carries the arbor of the balance, and *c* the plate or bridge for the second and third arbors and wheels. These plates *b* and *c* are curved, as represented, so as not to cover up the centre wheel of the watch. *d* and *e* are the ornamental bridges or plates for the escapement-wheel and lever, the neat, handsome, and peculiar shape of these bridges being highly ornamental, and allowing the wheel-work beneath to be clearly seen.

What I claim, and desire to secure by Letters Patent, is—

The design of the shape and configuration of the watch-plates or bridges shown in the drawing.

In witness whereof I have hereunto set my signature this twenty-ninth day of August, 1867.

A. GERARD.

Witnesses:

GEO. D. WALKER,

GEO. T. PINCKNEY.
